UNITED STATES PATENT OFFICE

JOSEPH W. KLEIN, OF LOS ANGELES, CALIFORNIA

DESIGN FOR A CHIME

Application filed October 17, 1929. Serial No. 33,080. Term of patent 14 years.

To all whom it may concern:

Be it known that I, JOSEPH W. KLEIN, a citizen of the United States, residing at Los Angeles, in the county of Los Angeles and State of California, have invented a new, original, and ornamental Design for Chimes, of which the following is a specification, reference being had to the accompanying drawings forming part thereof.

Fig. 1 is a view in front elevation of a chime embodying my new design.

Fig. 2 is a view in side elevation of the same.

I claim:

The ornamental design for a chime, as shown.

JOSEPH W. KLEIN.
